GRANT TRAIN DAVIS, OF CLINTON, MICHIGAN.

INTERNAL-COMBUSTION TURBINE.

1,160,145.

Specification of Letters Patent. Patented Nov. 16, 1915.

Application filed February 24, 1915. Serial No. 10,276.

To all whom it may concern:

Be it known that I, GRANT T. DAVIS, a citizen of the United States, and a resident of Clinton, in the county of Lenawee and State of Michigan, have invented a new and Improved Internal-Combustion Turbine, of which the following is a full, clear, and exact description.

This invention relates to improvements in devices for producing pressure by combustion, and has for an object the provision of an improved structure which will continuously produce pressure by internal combustion for use in operating a continuously moving turbine or other steam operated devices.

Another object of the invention is to provide a combustion chamber and a turbine chamber in axial alinement therewith together with means for supplying fuel and air in correct proportion to the combustion chamber whereby there will be produced a proper combustion, this chamber being also associated with a water inlet construction for supplying water which is utilized in absorbing most of the heat units for producing steam pressure, whereby the turbine is actuated.

A further object in view is to provide a device for continuously supplying steam under pressure through the instrumentality of an internally fired boiler.

In the accompanying drawings—Figure 1 is a longitudinal vertical section through a device embodying the invention; Fig. 2 is a sectional view through Fig. 1 on line 2—2.

Referring to the accompanying drawings by numerals, 1 indicates a base on which is arranged a tank 2 for containing fuel of some kind, as for instance hydrocarbon oil. This tank may be integral with base 1 or separate as desired. A tank 3 is provided adjacent tank 2 which acts as an air reservoir, the same being formed in any desired manner, as for instance integral with base 1 and tank 2. An air pump 4 is arranged in the tank 3 for maintaining any desired pressure of air in tank 3. The pump 4 is actuated through a worm gear 5 and a crank mechanism 6 of substantially any preferable kind as shown more particularly in Fig. 1, whereby the pump 4 operates in timed relationship to the movement of the shaft 7 and the power pulley 8. An opening 9 is provided between tanks 2 and 3 so that an air pressure may be exerted on the fuel in tank

3 and the same forced through the feed pipe 9 to the burner 10 where the same is mixed with air fed to the burner 10 through pipe 11 from tank 3. A valve 12 is provided in pipe 9 for regulating the fuel so that the amount of fuel and air fed to burner 10 will be in proper proportion for allowing a proper combustion in chamber 13. The burner 10 is provided with a valve 14 of any desired construction whereby the burner may be turned on and off. When the burner is first turned on the combustible mixture is ignited by a spark from a suitable spark plug 15. Usually the flame is maintained burning by a continuous supply of combustible matter, but if for any reason the flame should go out, the same may be easily ignited by a spark from plug 15. It is to be noted that the flame from burner 10 burns within an inclosed casing or chamber 13 which is formed from any desired material, and is provided with an extension 16 for receiving a turbine 17 of any usual or preferred type. In order to burn properly in the closed chamber 13, a sufficient quantity of air must be provided as just described.

In order to utilize the heat generated by the flame from burner 10 water is inserted into chamber 13 in sprays distributed over a large surface. In order that this may be readily done, and also continuously performed, the shaft 7 of the turbine 17 is hollow. As shown in Fig. 1, a casing 18 is provided which is in the nature of a water jacket, which water jacket supplies water to pipe 19, and pipe 19 is connected with the shaft 7 at 20 through the provision of any desired form of slip joint. The water passing through the turbine will be warm as the same is taken from the water jacket 18 and is sprayed in this condition by a nozzle 21, and also by a plurality of almost radial apertures 22. The nozzle 21 is arranged directly in the end of the hollow shaft 7, while the apertures or bores 22 extend from a point back of the end of the turbine to the periphery adjacent the edge. The discharge points of the apertures or bores 22 are so positioned that the discharge from all of the bores will be against a rounded surface 23 which may be formed integral with the walls of chamber 13, or may be a separate ring inserted at this point. As shown in Fig. 1, the deflecting ring 23 deflects the water from bores 22, and in deflecting the same causes a form of fan to be produced,

that is, a spreading of the water. A spreading or spraying of the water by the ring member 23 produces an encircling housing of vapor around the flame, and by reason of being finely divided the heat from the flame and the surrounding walls of the chamber quickly turns the vapor or sprayed water into steam. The nozzle 21 also produces a substantially conical-shaped spray which 5 surrounds one end of the flame and is converted into steam by the heat substantially as fast as the spray is forced into chamber 13. It is evident that the spraying of water into chamber 13 must be in proper proportion 10 to the heat provided by the burner 10 so as to produce steam, and also to produce the steam at the desired pressure.

The detailed construction of the turbine 17 may be of any kind as the same forms no 20 part of the present invention, and also the turbine may be arranged to receive steam from either end. In the drawing a supply pipe 24 is provided for directing the steam to an inlet header 25 so that the steam will 25 be fed to the blades of the turbine and finally discharged out the discharge header 26 which may be led to any convenient point. The turbine 17 is of course connected with the shaft 7 for rotating the 30 same, whereby power may be transmitted to pulley 8 which is rigidly secured thereto, and from pulley 8 to any device.

The invention contemplates the provision of means for producing steam through the 35 utilization of a flame in an inclosed chamber. This steam is shown in the drawing as being supplied to a turbine, but the steam may be used for other purposes if desired, or may be used for operating the turbine 17 40 and other devices without departing from the spirit of the invention. When it is desired to use the steam for other purposes besides operating the turbine 17, the valve 27 is closed and valve 28 is opened so that 45 the steam may pass through pipe 29 to the discharge device which is intended to utilize the steam. If it is desired to discharge a certain quantity of steam through pipe 26, and also to operate the turbine 17, both 50 valves 27 and 28 are opened.

In the drawing one adaptation of the invention has been disclosed, but it will be evident that a large number of variations 55 may be used without departing from the spirit of the invention, as for instance by substituting some other device for the turbine 17 and rearranging the various other parts so as to adapt the device to different locations and different conditions. It will 60 also be evident that the sprays from the water jets will protect the side walls of chamber 13 and prevent any overheating thereof.

What I claim is—

65 1. In an internal combustion turbine of

the character described, a cylindrical casing, a turbine filling one end of said casing, means for directing a flame substantially centrally of the chamber provided at the other end of said casing, a plurality of 70 means for providing a number of sprays of water which will substantially inclose or surround said flame, whereby the water is quickly converted into steam, and means for directing said steam to the inlet of said turbine. 75

2. In an internal combustion turbine, a cylindrical casing, a turbine structure arranged in one end of the casing and thereby producing a chamber at the opposite end, 80 means for supplying a continuous flame in said chamber, means arranged in said turbine for supplying water to said chamber, said water supplying means producing a substantially conical-shaped central spray 85 and a substantially tubular-shaped outer spray, whereby the water is finely divided and evenly distributed throughout said chamber for quickly absorbing heat units from the walls of the chamber and from 90 said flame, whereby steam is produced, and means for directing said steam to a point of utilization including said turbine.

3. In a device of the character described, means defining a chamber, means for maintaining a flame in said chamber, said chamber being entirely inclosed, water spraying devices opening into said chamber, said water spraying devices producing a substantially conical-shaped spray and a substantially cylindrical spray, both of said sprays surrounding to a certain extent said flame, whereby the heat from the flame may quickly convert the spray into steam, and means for directing the flame from said 100 chamber to a point of utilization. 105

4. In a device of the character described, a housing defining a closed chamber, a burner for projecting a flame into said chamber, means for supplying said burner with fuel, a pipe for supplying said burner with air, a compressed air chamber for supplying said pipe with air under pressure, a pump for maintaining a predetermined tension of air in said compressed air tank, 110 means for operating said pump including a power shaft, a motor for operating said power shaft, means for spraying water into said chamber whereby the heat from said flame will convert the water into steam, and means for directing said steam to said motor, whereby said power shaft will be rotated for operating said pump, and a power transmitting member connected with said power shaft whereby power may be taken 115 off of said power shaft. 120

5. In a device of the character described, an inclosed chamber, means for maintaining a flame in said chamber, means for providing a plurality of streams of water discharg- 130

- ing into said chamber, said means spraying the water so as to substantially surround said flame and thereby be sprayed into a thin conical shaped film or sheet for easy absorption of the heat created by said flame, a turbine arranged adjacent said chamber, means for directing the steam produced in said chamber to said turbine, and means for transmitting power from said turbine.
- 10 6. In a device of the character described, a housing defining a chamber, a turbine arranged to occupy part of said chamber, said turbine being provided with a hollow power shaft, and with a plurality of substantially radial bores on the inner end, a spray nozzle substantially central of said turbine on the inner end for spraying water, means for supplying water through said hollow shaft to said spray nozzle and to said bores, whereby a plurality of sprays are produced 20 in said chamber adjacent the turbine, means for maintaining a flame in said chamber, said flame being arranged substantially central of said sprays, whereby the heat is quickly absorbed by the water forming said 25 sprays, thus producing steam, and means for directing said steam to said turbine.
- 15 In testimony whereof I have signed my name to this specification in the presence of two subscribing witnesses.
